UNITED STATES PATENT OFFICE.

GEORGE B. LEWIS, OF SAN FRANCISCO, CALIFORNIA.

DESIGN FOR A CASKET.

42,767.

Specification for Design.

Patented July 9, 1912.

Application filed April 10, 1912. Serial No. 689,914. Term of patent 7 years.

To all whom it may concern:

Be it known that I, GEORGE B. LEWIS, a citizen of the United States, residing in the city and county of San Francisco and State of California, have invented a new, original, and ornamental Design for Caskets, of which the following is a specification, reference being had to the accompanying drawing, forming part thereof.

The figure is a perspective view of a casket showing my new design.

I claim:

The ornamental design for a casket as shown.

GEORGE B. LEWIS.

Witnesses:

GEO. C. SAMPSON,
F. A. DAILEY.
